UNITED STATES PATENT OFFICE

2,040,226

COLOR PRINTING ATTACHMENT FOR WEB
PRINTING PRESSES

Edward J. Watkins, Monrovia, Calif.

Application December 10, 1934, Serial No. 756,736

2 Claims. (Cl. 101—173)

This invention relates broadly to the art of multicolor printing and has to do more particularly with attachments for existing mono-color continuous web presses whereby two-color printing may be effected.

An object of the invention is to adapt mono-color or single impression web presses for two-color work at small expense and without reducing their capacity.

10 In continuous web printing presses it is necessary to provide a pair of feed rollers for pulling the web off the roll of news print and through the press, one roller delivering the web to the printing mechanism and the other pulling it through the printing mechanism and delivering it to the folding mechanism. These feed rollers must at all times maintain exactly the same peripheral speeds else the web will be broken or will become slack in the press. For this reason they are rigid, 15 usually being constructed of steel or iron, and are geared together to run in synchronism with each other and with the printing mechanism.

In accordance with the present invention, I 20 position a printing cylinder or cylinders to print on the web as the latter is passing over one or both feed rollers whereby the latter serve as backing members to support the web as the type is pressed thereagainst. Since the feed rollers have rigid and unyielding surfaces the printing face 25 or faces are made of rubber or other yielding resilient material to permit compensation for slight and unavoidable irregularities in the printing surfaces.

Although the invention is applicable to both 30 cylinder and flat bed printing presses, it has a larger field of usefulness in connection with flat bed presses and will now be described in connection with a conventional flat bed web press.

35 In the drawing:

Fig. 1 is a schematic diagram of a duplex flat bed web press equipped with my attachment;

Fig. 2 is a vertical detailed view, partly in section, of one of the feed rollers and a printing cylinder associated therewith in accordance with the invention; and

Fig. 3 is an enlarged detailed sectional view through a portion of the printing cylinder illustrating the manner of attaching the printing surface thereto.

40 Referring first to the schematic diagram of Fig. 1, that portion of the drawing that relates to an existing press is shown in light lines and the additional printing cylinders to be attached in accordance with my invention are shown in heavy lines.

The printing press itself comprises a feed roller 1 which continuously draws a web 2 from a roll of news print 3 and delivers the web over idler rollers 4, 5, and 6 to a lower printing mechanism comprising a pair of idler rollers 7 and 8 and an impression cylinder 9. From the roller 8 the web 2 is passed over a pair of idler rollers 10 and 11, thence back to an upper printing mechanism comprising idler rollers 12 and 13, and an impression cylinder 14, after which the web is 45 passed over an idler roller 15, under an idler roller 16, thence over a second drive cylinder 17, and thereafter under an idler roller 18 to a cutting and folding mechanism which has not been shown since it is immaterial to the present invention. 15

The two drive rollers 1 and 17 are rigid rollers and are of steel or iron geared together and to a driving motor to continuously feed the web at a uniform speed. The impression cylinders 9 and 14, together with their associated idler rollers 7, 20 8, 12, and 13, are all mounted on a reciprocable carriage and are reciprocated back and forth to carry the cylinders 9 and 14 over the stationary type beds 19 and 20, respectively, the mechanism for reciprocating these elements being driven 25 from the same mechanism which rotates the drive rollers 1 and 17 so that they all work in synchronism.

Of course, an inking mechanism is provided 30 for inking the type beds 19 and 20 but since these mechanisms are old and well known and have nothing to do with the present invention, they are not disclosed. During the intervals while the impression cylinders 9 and 14 are rolling over the type beds 19 and 20, the movement of the web 2 35 is stopped. During these intervals the slack which would otherwise accumulate between the drive roller 1 and the impression cylinder 9 is taken up by the idler roller 6, which is mounted on a lever 21, which is resiliently retracted by 40 springs not shown. At the same time the idler roller 15 moves to the left by a corresponding amount to permit the continuous feeding of the web over the drive roller 17. To maintain the web 2 in firm frictional engagement with the feed 45 rollers 1 and 17, a belt 22, mounted on three small idler rollers 23, 24, and 25, is positioned adjacent each roller 1 and 17, the belt following the curvature of the roller in each instance and firmly compressing the web thereagainst. 50

In the operation of the press as described, which is familiar to all those versed in the printing art, the impression cylinder 9 first forces the web 2 against the printing bed 19 to print on one side of the web and then later as the web 55

progresses through the press the same portion of the web is forced by the impression cylinder 14 against the printing bed 20 to print on the opposite side, the length of the loop of web between the beds 19 and 20 being adjusted by the proper positioning of the idler rollers 10 and 11 so as to insure proper registration of the printed matter on the opposite sides of the web.

In accordance with the present invention, I add to a press of the type described a pair of auxiliary printing cylinders 27 and 28, respectively. These cylinders are identical and are each connected to their associated driving roller in identical manner so that it will be sufficient to describe the installation of the cylinder 27.

Referring to Figs. 2 and 3, cylinder 27 comprises a hollow tubular member 29, preferably of iron or steel, suitably supported as by spokes 30 on a shaft 31, which extends beyond the cylinder 27 at each end and is rotatably supported in bearings provided therefor in the main frame 32 of the printing press. Mounted upon the shaft 31 at one end of the cylinder 27 is a hub 33 which is keyed to the shaft by a key 34. This hub 33 in turn supports a gear 35 which meshes with a gear 37 mounted upon the shaft 38 of the drive cylinder 17. This shaft 38 may be driven through a beveled gear 39 mounted upon the opposite end, which meshes with a suitable drive pinion connected with the mechanism of the press.

The construction of the hub 33 and gear 35 permits rapid removal of the gear 35 from driving relation with the hub 33. Thus by merely removing the cap screws 36, the gear 35 may be slid out of mesh with the gear 37. This is done whenever it is desired not to use the color printing cylinder.

The number of teeth in the gears 35 and 37, respectively, is so chosen relative to the diameters of the drive rollers 17 and the printing cylinder 27 that they travel at substantially the same peripheral speeds. Actually the cylinder 27 travels slightly slower because of the fact that the type thereon extends outwardly beyond the surface of the cylinder and it is desired that the surface of the type travel at the same speed as the web which rides over the drive cylinder 17.

The area of the printing surface 40 on the cylinder 27 varies widely according to the particular requirements of the job at hand. Ordinarily the cylinder will be employed to add red or green (or any other color for that matter) headings or inserts to a page of printed matter, the major portion of which will be printed in black from the usual printing face 19. Thus in Fig. 2 the web 2 has been completely printed in black from the type bed 19, with the exception of a blank space 41 which is to be printed in color from the cylinder 27. In this instance the cylinder 27 therefore carries a small printing surface 40 dimensioned to fill the blank space 41 on the web.

As previously indicated, the printing surface on the cylinder 27 must be resilient to work satisfactorily against the rigid drive cylinder 17. I prefer to employ a printing surface of rubber since methods of producing such faces are well known in the printing art and they can be made quickly and at small expense. The rubber printing face must be securely fixed to the surface of the cylinder 27 and I have found it desirable in practice to first mount on the cylinder 27 a strip of cardboard or other porous fibrous ma-

terial 42 and then affix the rubber printing face 43 to the cardboard, the cardboard being affixed to the cylinder 27 by a suitable cement and the rubber printing face 43 likewise being cemented to the cardboard 42. I have found this procedure to be much more satisfactory than cementing the rubber mat or face 43 directly to the surface of cylinder 27 because the cements that are suitable for the purpose are extremely slow in setting when used between two non-porous surfaces. However, when the cement is used against a porous surface, such as the cardboard 42, it sets very rapidly.

It is highly desirable, if not absolutely necessary, in an attachment of the type described to be able to quickly and accurately properly position the printing surface 40 on the cylinder 27 so that it registers with the other printed matter on the web. To this end, I subdivide the surface of the cylinder 27 by longitudinal lines 46, 20 these lines being spaced circumferentially to indicate, in terms of lines, the vertical position on the printed sheet. Thus the line labeled "T" on the right end of cylinder 27 indicates the top of the printed page and the line "B" immediately therebelow indicates the bottom of the printed page. The side margins of the printed page may also be indicated by circumferential lines 44 engraved in the surface of cylinder 27.

The device may be set up and operated in the following manner: Assume that the printing bed 19 has been prepared and that certain blanks have been left therein for the insertion of color matter. At the same time the rubber printing surfaces, corresponding in dimensions to the blanks left in the bed 19, are prepared. They are then cemented to the surface of the cylinder 27 (with a cardboard backing as previously described) in the proper position to register with the blank areas of the bed 19, the circumferential 40 positioning of the printing face 40 being determined by following the longitudinal lines 46 and the lateral position being determined by suitably spacing the surface 40 from one of the marginal lines 44. The press is then set to a predetermined normal position; then the cylinder 27 is rotated until one of the longitudinal calibrating lines, labeled "R" on the left margin, is aligned with a pointer 45 secured to the frame of the press. The gear 35 is then placed in position on the hub 33 and locked in place by inserting and tightening the cap screws 36. By following the foregoing procedure the press may be set up and operated with assurance that the color inserts will be accurately registered with respect to the black printing matter.

Inking mechanisms 27a and 28a are provided for the auxiliary cylinders 27 and 28, respectively, but since these mechanisms are well known, they are merely schematically illustrated in Fig. 1 and need not be described in detail.

Although the invention has been described with reference to a particular installation on a flat bed press, it is to be understood that various modifications can be made in the structure disclosed to better adapt it to special operating conditions without departing from the spirit of the invention and the invention is therefore to be limited only as set forth in the appended claims.

I claim:

1. A flat bed web printing press comprising a printing mechanism and two rigid feed rollers, one of which feeds a web to the printing mechanism and the other of which discharges the web

from the printing mechanism, in combination with an auxiliary printing cylinder having a resilient printing face thereon and positioned to print on the web as the latter passes over one of said feed rollers whereby the rigid feed roller constitutes a backing member to compress the web against the auxiliary printing cylinder, and

means for driving said auxiliary cylinder in synchronism with said feed roller.

2. The combination as described in claim 1 in which a second auxiliary printing cylinder is provided in association with said other feed roller 5 for printing on both sides of the web.

EDWARD J. WATKINS.
